UNITED STATES PATENT OFFICE

131,136

DESIGN FOR A FALSE FACE

Carrie Balaban, Chicago, Ill.

Application November 5, 1941, Serial No. 104,029

Term of patent 3½ years

To all whom it may concern:

Be it known that I, Carrie Balaban, a citizen of the United States and resident of Chicago, in the county of Cook and State of Illinois, have invented a new, original, and ornamental Design for a False Face, of which the following is a specification, reference being had to the accompanying drawing, forming a part thereof.

Fig. 1 is a front elevational view of a false face, showing my new design.

Fig. 2 is a top plan view of the same.

Fig. 3 is a sectional view taken through the false face, along the line 3—3 of Fig. 1.

I claim:

The ornamental design for a false face, substantially as shown.

CARRIE BALABAN.
